(57) **CLAIM**

The ornamental design for a strap for journal, as shown and described.

DESCRIPTION

FIG. 1 is a front view of a strap for journal showing my new design.

FIG. 2 is a rear view thereof.

FIG. 3 is a front view thereof, with the journal in an open position.

FIG. 4 is a rear view thereof, with the journal in an open position.

FIG. 5 is a left side view thereof.

FIG. 6 is a right side view thereof; and,

FIG. 7 is a bottom view thereof.

The broken lines showing the journal illustrate the environment of the claimed design and form no part of thereof.
